UNITED STATES PATENT OFFICE.

FRED MACK GLOVER, OF WEST POINT, GEORGIA.

PESSARY.

Application filed February 26, 1923. Serial No. 621,454.

To all whom it may concern:

Be it known that I, FRED MACK GLOVER, a citizen of the United States, residing at West Point, in the county of Troup and State of Georgia, have invented certain new and useful Improvements in Pessaries, of which the following is a specification.

My invention relates to improvements in pessaries, the primary object thereof residing in the provision of such an article that may be readily applied, and is of such a nature that when applied will effectively maintain the womb in its correct position, the nature of the same being such as not to interfere with the womb discharges.

A further object of my invention is the provision of such a pessary that may be comfortably worn without the usual irritation of the vagina nor the compression of the rectum, my article consisting of a soft, pliable sponge rubber material.

Having the above and other objects in view, the nature of the invention will be better understood by a consideration of the following specification and drawings.

In the drawings, wherein like reference characters indicate corresponding parts throughout the several views,

Figure 1. is a vertical cross sectional view of my improved pessary, applied.

Figure 2. is a top plan view of the article, per se, and,

Figures 3. and 4. are perspective and vertical cross sectional views respectively of the pessary.

Referring to the drawings in detail, 5 designates the pessary which consists of a

body, preferably in the shape as shown, of soft and pliable sponge rubber. The edges of the body are rounded; and in the upper end thereof is formed a pocket 6, the bottom wall 7 of which is curved outwardly and terminates at the front face of the said body. The upper end of this pocket is cut inwardly of the front edges 8 thereof, to prevent accidental displacement of the womb from the pocket 6 when the same is disposed therein in a manner clearly shown in Figure 1.

In view of the above description it will at once be apparent that I have provided a pessary that is a substantial improvement over the art and one that will fully anticipate the above ascribed objects.

Although I have herein shown and described the preferred embodiment of the present invention it is nevertheless to be understood that minor changes may be made therein without departing from the spirit and scope of the invention as claimed.

Having thus described my invention, what I claim as new and desire to secure by Letters Patent, is:—

In an article of the class described, a longitudinally pliable body of soft rubber formed in its upper end with a womb receiving pocket, the upper end of said pocket being cut inwardly of the front edges thereof for preventing displacement of the womb therefrom, and said pocket opening upon one end and upon one of the vertical faces of said body.

In testimony whereof I affix my signature.

FRED MACK GLOVER.
